[57] **CLAIM**

The ornamental design for a tongue and tooth cleaning brush, as shown and described.

DESCRIPTION

FIG. 1 is a right end, top and front perspective view of the tongue and tooth cleaning brush showing my new design;

FIG. 2 is a left end elevational view thereof, the right end being a mirror image of the left end shown in FIG. 2;

FIG. 3 is a front elevational view thereof, the rear being a mirror image of the front shown in FIG. 3;

FIG. 4 is a top plan view thereof; and,

FIG. 5 is a bottom plan view thereof.

FIG. 1

FIG. 2

FIG. 3

FIG. 4

FIG. 5
